PRESSURE OPERATED SWITCH

Ralph A. Nicholson, Chicago, Ill., assignor, by
mesne assignments, to Lyon Industries, Inc.,
New York, N. Y., a corporation of Delaware

Application December 28, 1945, Serial No. 637,695

1 Claim. (Cl. 200—83)

1

This invention pertains to fluid handling, regulating, and distributing apparatus, and has as its principal object the provision of a carbonator and control means therefor for use in conjunction with beverage dispensing systems and the like, whereby water is charged with carbon dioxide gas for beverage purposes.

It is a further object to provide carbonating means of increased efficiency, simplified construction, and optimum reliability in automatic operation.

Further objects are, the provision in a device of the class described of: carbonating means and method whereby water at lowered, regulated, temperature is atomized or finely divided and projected into an atmosphere of carbon dioxide gas for substantially instantaneous absorption; to the provision of means in the carbonating chamber for refrigerating the carbonated water for retention of the absorbed gas; to the provision of means structurally and operatively associated with the carbonating chamber for automatically regulating the injection of water into the gaseous atmosphere independently of any gas pressures existing in said chamber and within close limits as regards volumetric liquid levels to be maintained in said chamber; to the provision of a carbonator of unitary construction embodying the foregoing features and for practice of the foregoing method; to the provision of automatic liquid-level control means of general application and particularly adapted for cooperation with said carbonator as a structural part thereof.

Additional objects and aspects of novelty in the invention relate to details of construction and operation of one preferred embodiment thereof described hereinafter in view of the annexed drawings in which:

Fig. 1 is a vertical section through the novel carbonator and the liquid-level control means forming part thereof, with diagrammatic connections to certain fluid supply and dispensing lines;

Fig. 2 is a horizontal section taken along lines 2—2 of Fig. 1;

Fig. 3 is a vertical section, to enlarged scale, of the liquid-level control means viewed from a side adjoining that shown in Fig. 1;

Referring to Fig. 1, the novel carbonator includes a metal chamber 10 having openings in its upper and lower ends, and a top closure plate 11 removably secured in position by bolt means 12 engaged in a top flange 13 drawing the plate and its gasket 14 against the upper peripheral edge portion of said chamber.

2

Depending centrally of the top closure plate is a water injecting and atomizing means in the form of a head 15 provided with a plurality of spray or nozzle outlets 16, and connected to a source of supply of cooled water through conduit or line 17.

Means providing an atmosphere of carbon dioxide gas in the region adjoining said injecting means, includes a conduit or pipe 18 adapted for connection with a source of supply 19 of CO₂ gas under pressure of approximately 30# p. s. i. such as supplied in commercial cylinders well known in the art, said pipe having an outlet 20 situated substantially opposite the injecting

head 15.

The water to be carbonated enters chamber 10 from line 17 through the injecting head 15 and will be permitted to reach a predetermined level in the chamber, which level is desirably automatically maintained by means hereinafter described; and in order to prevent spilling of the gas from the carbonated water following carbonation, that is, to prevent escape of any appreciable amount of absorbed gas from the water, the interior of said chamber and its liquid content is refrigerated, as by a coil 21 having terminal refrigerant inlet and outlet connections 22 and 23 connected with a source 24 of temperature-controlled refrigerating fluid, for example any of a number of refrigerating machines of conventional type well known in the art, and adapted to circulate a refrigerating or cooling medium through coils 21 and thereby maintain a desired temperature in the carbonated water in chamber 10, said water being drawn off for beverage purposes through dispensing outlet 25 into dispensing line 26.

Means for automatically maintaining a predetermined liquid level in chamber 10 includes 40 a weight-sensitive member and closure in the nature of a diaphragm 30 clamped between a bottom flange 31 on the chamber and a second chamber 32 secured to said flange as by screws 33 (Fig. 3 also), said diaphragm being sealed to 45 prevent leakage from the bottom of chamber 10 and being yieldable to the weight of the carbonated water for displacement, vertically, of a central post 34, Fig. 3, attached to the diaphragm by nut 35, said post guidedly reciprocating on a 50 stud 36 having a bottom portion 37 fixed on the inner bottom portion of chamber member 32.

Spring means 38 on the guide stud normally urges the post portion 34, and hence the connected diaphragm 30, upwardly against the 55 weight of water in chamber 10, and when the

desired volume of water is present in said chamber 10, its weight acting through or against diaphragm 30 overcomes the effort of spring 38 to flex the diaphragm downwardly and actuate certain control or switch means 40 accordingly.

The control or switch means 40 is preferably in the nature of a small mercury switch of known type, and usually having a cylindrical glass envelope, which is held in a clamp 41, Fig. 3, attached in turn to a sleeve 42 rockably mounted by nut and bolt means 43 between the upper free ends 44 of a U-shaped bracket 45 secured to the inner floor of the second chamber member 32 adjacent the diaphragm post structure, in the relationship shown in Fig. 2.

An operating connection between the diaphragm or weight-sensitive structure, and the control or switch means is provided by a pin 50, Fig. 2, secured as at 51, to a clamp 52 engaging the switch 40 at a point radially displaced from the rocking axis afforded by the switch mounting means 42—43—44, said pin, as in Fig. 3, projecting horizontally into a slot 53 in the post portion 34 of the diaphragm, such that as the latter moves up and down responsive to changes in water level, this motion is transmitted through pin 50 to switch clamp 52 to rock the switch 40 correspondingly.

Means eliminating or nullifying the loading effect of gas pressures in chamber 10, upon the weight-sensitive means, includes a by-passing pipe or line 60, Fig. 1, having an upper inlet opening 61 in chamber 10 about opposite the injecting nozzle 15, and a lower terminal outlet 62 connected with a known type of moisture trap 63 continuing communication of line 60, through piping 64 into the bottom portion of the second chamber portion 32, as at 65, by reason of which contrivance the pressure within chamber 10, on one side of diaphragm 30, is communicated to chamber 32 and the opposite side of said diaphragm 30, balancing out any loading effect of such pressure upon the diaphragm, so that the latter is subjected only to the displacing effort of the carbonated water in the main or upper chamber 10, on the one hand, and to the counter-effort of the spring means 38, on the other hand.

Connections through said switch 40 for controlling flow of water to chamber 10 includes leads 70 from the switch to a known type of water pump 71, Fig. 1, through power source 72, such that when the switch is in its normal position, as shown with the diaphragm 30 lowered under weight of water in chamber 10, switch 40 is open and pump means 71 is not operating; but when the water level in chamber 10 drops to a predetermined level, as by withdrawal of carbonated water through dispensing line 26, the effort of spring 38 acting through post means 34 flexes the diaphragm upwardly, thus rocking the switch 40 to close circuit from power source 72 through leads 70 to energize the pump means 71, which will force water from a cold water supply source 75 through line 17 into the atomizing injection means 15. The cold water, broken up into fine particles by means 15, intermingles with the gas, in the upper portion of chamber 10, adsorbing optimum volumes thereof and returns to liquid state in the bottom of the chamber 10; when the liquid level again reaches the desired and predetermined point, the weight of the liquid, that is, the carbonated water, will overcome the effort of spring or counteracting means 38 to restore the diaphragm 30 to normal, upwardly displaced, condition, with a corresponding

restoration of the switch 40 to normal open circuit condition, thereby stopping the water-supplying or pump means 71 until the foregoing cycle of operations shall be repeated responsive to a further drawing off of carbonated water through the dispensing line 26.

Means for automatically or manually relieving excess gas pressure in chamber 10 includes a relief valve 80, Fig. 1, mounted on the head plate 11 and adapted to act automatically, when greater than a predetermined pressure exists in chamber 10, to permit escape of gas through port 81, said valve being operable manually by manipulation of toggle handle 82 with the same result.

In the foregoing construction, it is understood that the sensitivity of the diaphragm 30 to liquid displacement may be determined by selection of appropriate spring tension 38, and by appropriate dimensioning in a vertical sense of the slot 53 for the switch operating pin 50.

Summary of operation

The operation of the device and practice of the method hereinbefore described in detail is summarized in view of Fig. 1 with the assumption that a predetermined volume of carbonated water, for example something over half of the capacity of chamber 10, is to be maintained in the carbonating chamber at all times.

Accordingly, the tension of the diaphragm compensating spring 38 is selected to yield under the weight of said predetermined volume of water on the diaphragm 30, by reason of which the diaphragm post structure 34 is pressed downwardly thereby tilting the switch 40, through the pin and slot means 50, 51, 52, 53, Figs. 2 and 3, to dispose the switch in open circuit condition. At this time, no water is leaving the injector 15, but there is a constant head of gas from supply line 18, 19 in chamber 10, adequate to force the water through the dispensing line 26.

Assuming that now a substantial quantity of carbonated water is withdrawn from chamber 10 for beverage purposes or the like, a point of liquid level will be reached in chamber 10 where the liquid contents of the latter becomes insufficient to overcome the effort of diaphragm spring 38, so that the diaphragm 30 and associated post structure and switch actuating means 34, 50, 51, 52, 53, tilts the switch clockwise, Fig. 1, to close an operating circuit from power source 72 to energize the water pump means 71, thereby forcing cold water from source 75 at considerable pressure, for example about 60# p. s. i. through line 17 and into the injecting means 15, said cold water issuing from the atomizing nozzle means 16 in finely divided state to mingle with the carbon dioxide gas in the upper portion of chamber 10 and absorb optimum volumes thereof quickly, the water particles and adsorbed gas content collecting in liquid state as carbonated water in the lower portions of chamber 10 until a sufficient weight of such water accumulates (very rapidly) to depress diaphragm 30 and restore the switch 40 to open circuit condition, stopping the pump and the atomizing operation.

In accordance with this method, the water supplied to the carbonator is already at reduced temperature in order that the greatest volume of carbon dioxide gas may be absorbed when the finely divided water is exposed to the gas; by atomizing the water the surface area of any given volume thereof is vastly expanded so that the absorption occurs almost instantly, in contrast to the action of prior carbonators which rely

upon mechanical agitators and the like for commingling the gas and water.

Retention of the absorbed gas is further assured by cooling the collected or reformed water and its gas content within the carbonator itself, as by the means 21, 22, 23, 24.

The gas pressure on opposite sides of the control diaphragm 30 is balanced by the by-passing means 69, 61, 62—65, the trap 63 serving to prevent accumulation of moisture in the lower or second chamber 32.

The device and method of the present disclosure may be utilized in conjunction with various beverage dispensing systems, for example that shown in my copending application Serial No. 616,855, alone or in conjunction with the carbonated water circulating means disclosed in my copending application Serial No. 611,633, the present disclosures constituting an inventive extension of the liquid-level controlling and carbonating means shown in my copending application Serial No. 611,634, now Patent No. 2,481,612 granted Sept. 13, 1949.

It is contemplated that the apparatus and method herein set forth may be utilized for other than beverage purposes, and for other than carbonating purposes, and no limitations on the scope of the invention are intended by the specific recitations herein set forth, excepting as may be expressly provided in the appended claim.

I claim as my invention:

A liquid-operated control unit for mounting on open bottomed chambers in carbonators and the like, said unit comprising a cup-shaped vessel having a mounting flange on its open

mouth portion and adapted to be clamped by means engaging said flange to close the bottom of a chamber as aforesaid, a diaphragm seated and clamped on said flange between the latter and a rim portion of said chamber, a depending post secured centrally of said diaphragm, an upwardly extending guide stud for said post and secured centrally on the floor of said vessel, a spring between said stud and post to urge the latter and said diaphragm normally upward, a bracket mounted adjacent said post on the floor of the vessel, a switch rockably mounted by said bracket, an operating pin extending from said switch into a slot in said post for movement responsive to displacements of said diaphragm to actuate said switch, and sealed leads in a wall of said vessel for conductor means connected to said switch and passing outwardly of said vessel, and means in a wall of said vessel providing egress for displaced air.
